Primary Examiner — Wan Laymon*Assistant Examiner* — Clint A Samuel(74) *Attorney, Agent, or Firm* — Kilpatrick Townsend & Stockton LLP(57) **CLAIM**

The ornamental design for a light fixture with rotatable end, as shown and described.

DESCRIPTION

FIG. 1 is a perspective view of a light fixture with rotatable end showing our new design with the rotatable end in a first orientation;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is an additional perspective view of the light fixture with rotatable end showing the rotatable end in a second orientation.

The broken line disclosure—including the grille depicted on the rotatable end—represents portions of the fixture which form no part of the claimed design.

The light fixture with rotatable end is shown with a symbolic break in its length. The appearance of any portion of the article between the break lines forms no part of the claimed design.
